UNITED STATES PATENT OFFICE.

CLINTON E. WOODS, OF CHICAGO, ILLINOIS.

DESIGN FOR A CASE FOR DYNAMOS.

SPECIFICATION forming part of Design No. 25,329, dated March 31, 1896.

Application filed February 8, 1896. Serial No. 575,653. Term of patent 7 years.

To all whom it may concern:

Be it known that I, CLINTON E. WOODS, a citizen of the United States, residing at Chicago, county of Cook, and State of Illinois, have invented and produced a new and original Design for Cases for Dynamo-Electric Machines, of which the following is a specification.

My invention relates to a design for frames or cases for dynamo-electric machines, and is illustrated in the accompanying drawings, wherein—

Figure 1 is a longitudinal section through a dynamo-electric machine case or frame, showing my design. Fig. 2 is a perspective view of the same.

I deem these two figures sufficient to fully illustrate my design.

The leading features of my design consist of a substantially oblong or rectangular case

having inwardly-projecting parts integral therewith, the inner ends of said projecting parts being curved, as shown.

A is the outer case, having integral therewith the inwardly-projecting parts B B, the inner ends of said inwardly-projecting parts being curved, as shown. The case A has a projecting ring C on one side. The case is provided with an opening extending therethrough, the ends of said opening being within the ring C.

I claim—

The design for the case or frame of a dynamo-electric machine substantially as herein shown and described.

CLINTON E. WOODS.
